UNITED STATES PATENT OFFICE.

CHARLES E. CHAPMAN, OF FORT EDWARD, NEW YORK, ASSIGNEE OF ONE-HALF TO
JOSEPH GOODFELLOW, OF FORT EDWARD, NEW YORK.

APPARATUS FOR BURNING HYDROCARBON OILS.

1,419,223.

Specification of Letters Patent. Patented June 13, 1922.

Application filed November 30, 1920. Serial No. 427,336.

To all whom it may concern:

Be it known that I, CHARLES E. CHAPMAN, a citizen of the United States, residing at Fort Edward, in the county of Washington 5 and State of New York, have invented certain new and useful Improvements in Apparatus for Burning Hydrocarbon Oils, of which the following is a specification.

This invention relates to an apparatus for 10 burning hydrocarbon oils and is an improvement in the invention disclosed in my co-pending application Serial No. 365770, filed by me in the United States Patent Office March 15, 1920:

15 In the application above referred to, the apparatus disclosed is so constructed that crude oil and steam are co-mingled and nebulized in a jacketed retort, a portion of 20 the heated products of combustion being circulated through the retort during nebulization and thus practically excluding air with the result that the chemical structure 25 of the oil and steam is broken down into products which result in an intensely hot flame.

In this present invention the same general principle of operation is employed, but the apparatus is modified by the use of a refractory lining in the retort thereby preventing 30 burning out of the retort under the influence of such an intensely hot flame.

Also the apparatus is constructed in such a manner that the refractory lining may be made in sections and inserted into the retort 35 and bell-mouth during assembly of the apparatus.

Other modifications from the original invention will appear in the following description at which time the advantages resulting 40 therefrom will be enumerated.

In the drawings:

Figure 1 is a longitudinal section in a vertical plane through the apparatus of the present invention.

45 Figure 2 is a front elevation.

Figure 3 is a transverse vertical section on the line 3—3 of Figure 1.

In detail:

The apparatus is adaptable for use as a 50 burner for crude oils and the like in furnaces, core ovens, enameling ovens, or in any location where intensely high heat is required.

55 The apparatus consists of a shell-like body 2 of substantially cylindrical form and

having feet 3. At the rear end the said cylindrical body 2 is closed by a back plate 4 suitably held in place by bolts 5 and nuts 6, said bolts passing through the peripheral flange 7 of the cylindrical body 2. 60

At the forward portion of the cylindrical body 2, as clearly shown in Figures 1 and 2, there is formed a projection 8 having a curved face adapted to receive the body portion of the retort tube 9 with its overlying refractory covering 9^a which is of tubular form and slips over the retort tube 9 in the manner hereinafter described. Bolts 10 extend through the projection 8 and into the outer wall 9 of the retort tube for supporting the retort tube in position. 70

The retort tube 9 comprises spaced cylindrical walls 10 and 11 thus providing a cooling fluid space 12 therebetween. The rear end of the retort tube 9 is flanged as indicated at 13 to connect with a flange 14 on the bell-mouth 15 held thereto by the bolts 16 and nuts 17. The bell-mouth has a curved throat as indicated at 18 and is split longitudinally and flanged on each side of each 80 half as indicated at 19, the two halves being secured together by bolts 20. Previous to assembling the two halves a refractory liner 21 having identically the shape of the inner surface of the bell-mouth and its complementary throat is inserted between the halves and is thus held by the bolting of the halves together. 85

A tubular member 22 of refractory material is inserted on the interior of the retort 90 tube 9 and is provided with an enlarged nebulizing chamber entrance 23 by reducing the thickness of the wall of the said member 22. In this member 22 is formed an opening 24 which is concentric with a smaller but 95 similar opening 25 through the bottom of the retort tube 9 and which receives a thimble 26 of refractory material, the flange 27 of which rests on the wall of the retort tube while the body portion projects downwardly 100 through the retort tube and its refractory cover 9^a. A head piece 28 also of refractory material is inserted in the end of the retort tube and held in place by the end plate 29 which is secured to the retort tube 9 by 105 screws 30 or other suitable means. Both the head piece 28 and plate 29 are centrally apertured to receive the injector tube 31 having the nozzle 32 and which at its head end is provided with a flange 33 resting against 110

the end plate 29 and secured in place by the face plate 34 secured to the end plate 29 by bolts 35 and having a flange 36 which rests in a counter bore in a refractory head 37 thus completely enclosing the exterior of the retort tube 9 in a casing of refractory material up to the point where the covering 9^a ends. At the forward end of the cylindrical body 2 and extending inwardly thereof as far as the bell-mouth 15 and lying closely against the wall of the said body 2 is a lining of refractory material as indicated at 38 and upon which, at the forward end of the apparatus is located the superheater 39 of semi-circular form in cross-section and having the reduced receiving edge 40 pointed toward the bell-mouth 15.

Cooling water for the jacket 12 is led in by the pipe 41 at the rear end of the retort tube 9 and is taken off by the pipe 42 on the side as clearly shown in Figure 3.

Steam from a suitable steam generator is led into the superheater through a pipe 43 and is superheated by the flame playing upon the superheater and leaves the said superheater by a pipe 44 having flanged connection as at 45 with a pipe 46 leading to a cross T 47 into the opposite side of which crude oil is fed by a pipe 48. At right angles to these pipes 46 and 48 is a nipple connection 49 with the said cross T 47 which connects the head 50 of a mixing chamber 51 with the steam and oil supply, the other end of the mixing chamber being closed by a similar head 52 connected by an elbow 53 and flange joint 54 with the nozzle tube for feeding the co-mingled oil and steam to the nozzle. Within the mixing chamber 51 are the two conical perforate baffles 55 which point toward the nozzle tube and serve to finely divide the oil and steam and are of special advantage in initially starting the burner at which time the crude oil is in more or less of a coagulated condition and is only acted upon by steam entering through the connection 56 which is connected with a steam generator but not a superheater and is used for starting purposes only, said connection having a valve 57 for shutting off the supply of steam from this source as soon as the burner is started.

It is to be noted that the perforate baffles 55 are supported on shoulders 58 having conical seats and are thus capable of removal by simply unscrewing the head 50 of the mixing chamber.

In operation, the burner is started by opening the valve 57 which thus permits oil and steam to co-mingle in the mixing chamber 51. The burner is then lighted at the nozzle or bell-mouth 15 and the flame plays on the superheater 39 superheating the steam which is fed thereto and the valve 57 is then shut off and the superheated steam and oil

are thus permitted to co-mingle in the chamber 51. When this is done the flame from the burner undergoes a complete change in physical characteristics, the flame which was of a reddish hue when using steam which was not superheated first becomes blue and then turns to a bluish pink of intense heat. 70

I claim:

1. The herein described apparatus for burning fuel oils, comprising a cylindrical jacketed retort chamber provided with a discharge horn having a bell-mouth, said horn being split longitudinally, means securing the horn parts together, a refractory cylinder fitting the retort chamber providing a 80 lining therefor, a sectional refractory lining having the sections thereof clamped in assembled relation between the parts of the said horn fitting the horn, a steam superheater located approximate the bell-mouth 85 and receiving the discharge therefrom, an oil supply including nebulizing means discharging into the retort chamber, and means connecting the oil supply with the steam supply from the superheater. 90

2. The herein described apparatus for burning fuel oils, comprising a water jacketed retort chamber provided with a discharge horn having a bell-mouth, said horn being split longitudinally, means securing the horn parts together, a refractory lining for the retort chamber, a refractory lining assembled between the parts of the said horn, a cover of refractory material enclosing the jacketed retort chamber, a steam superheater 100 located approximate the bell-mouth and receiving the discharge therefrom, an oil supply including nebulizing means discharging into the retort chamber, and means connecting the oil supply with the steam supply 105 from the superheater.

3. The herein described apparatus for burning fuel oils, comprising a jacketed retort chamber provided with a discharge horn having a bell-mouth, a steam superheater located approximate the bell-mouth and receiving the discharge therefrom, an oil supply including nebulizing means discharging into the retort chamber, a mixing device 110 having perforate conical baffles receiving the oil supply, and means connecting the mixing device with the steam supply from the superheater. 115

4. The herein described apparatus for burning fuel oil, comprising a jacketed retort chamber provided with a discharge horn having a bell-mouth, a refractory lining for the retort chamber, an exterior refractory cover for said chamber, a refractory lining for the discharge horn, an enclosing cylinder closed at one end, and a refractory lining at the open end of said enclosing cylinder and approximate the mouth of the discharge horn. 125

5. The herein described apparatus for 130

- burning fuel oils, comprising a jacketed retort chamber provided with a discharge horn having a bell mouth, a hollow arcuate superheater located approximate the bell mouth and receiving the discharge therefrom, an oil supply including nebulizing means discharging into the retort chamber, and means connecting the oil supply with the steam supply from the superheater.
- 10 6. The herein described apparatus for burning fuel oils, comprising a jacketed retort chamber provided with a discharge horn having a bell mouth, a hollow arcuate superheater located approximate the bell mouth to receive the discharge therefrom and provided with a reduced receiving end, an oil supply including nebulizing means dis-

charging into the retort chamber, and means connecting the oil supply with the steam supply from the superheater.

20

7. The herein described apparatus for burning fuel oils, comprising a jacketed retort chamber provided with a discharge horn having a bell mouth, a steam superheater located approximate the bell mouth and receiving the discharge therefrom, an oil supply including nebulizing means discharging into the retort chamber, a mixing device receiving the oil supply, and means connecting the mixing device with the steam supply from the superheater.
